17 Claims. (Cl. 233—11)

In "closed" centrifuges in which the liquid is supplied to and discharged from the centrifugal bowl through fixed pipe lines which are tightly connected to the bowl by packing boxes of some kind, the material of the packing is exposed to the risk of serious damage if the centrifuge be rotated for some length of time with no liquid in the packing boxes. Owing to the very high number of revolutions of the bowl, which causes a very high relative velocity between the tightening surfaces, a very considerable amount of heat is generated even when a material is chosen which in all respects is suited to the purpose. The heat produces a dangerous rise of temperature if such rise be not removed by effective cooling. It should be borne in mind that a centrifugal bowl has a very great moment of inertia compared with the rotating parts of other machines, for instance centrifugal pumps, the rotation speed at the same time being very high. After the centrifugal bowl has attained its full number of revolutions, it therefore possesses a great amount of kinetic energy, which must be applied during the starting period, but owing to the capacity of the driving motor and the resistance of the transmission members, only a limited amount of energy can be transmitted per time unit, and a considerable time is therefore required to transmit the necessary amount of energy to the centrifugal bowl. As compared with a centrifugal pump or the like, the starting time is therefore many times longer and may amount to about ten minutes. Another circumstance which should not be overlooked is the fact that the liquid must not be fed into the centrifuge until it has reached its full number of revolutions, since the liquid is not treated in a satisfactory manner unless the centrifugal force has attained its full value. A centrifugal pump, on the other hand, must be filled with liquid at the start in order to put it into operation. With a pump it is therefore not necessary to take any special measures to avoid the risk of the packings being damaged by too high a temperature, but with a centrifuge having similar packings the conditions are quite the reverse. With a centrifuge, special steps must be taken in order to avoid damage to packings while the centrifuge is gradually speeding up to its normal operating speed.

The present invention comprises a method and means of protecting the material of the packing against the risk of becoming damaged by the frictional heat generated during the starting operation by effectively cooling the packing boxes during the whole or the greater part of such starting operation. A sufficient cooling can be effected if

the separation liquid which is normally contained in the packing box is present therein at the start. It is also possible to bring about the cooling by means of a special liquid, which may either be fed to the packing boxes before the start of the centrifuge in some suitable manner, for instance by a cock or the like, or which may be caused to circulate through the packing boxes by means of suitable devices. The best method of effecting the required cooling is, however, in most cases, to make the liquid to be separated stream in a closed circuit through the centrifuge before, at, or immediately or soon after the start. In a centrifuge of the type referred to, it is necessary to force the liquid through the centrifugal bowl by means of some pumping device. The circulation mentioned may be brought about simply by starting the pump at the right moment after a special return pipe has been opened. It is not, of course, quite necessary that the circulation of the liquid should begin at the start of the centrifuge, since no dangerous generation of heat takes place at the tightening surfaces of the packing boxes while the machine rotates at a comparatively low speed. As the speed increases, the heat generation per time unit also increases, so that the temperature tends to rise progressively. In any case the cooling process must be in operation before the centrifuge has attained its full R. P. M.

When a limited quantity of liquid is introduced into the packing boxes at the start, the fixed pipes connected with the centrifuge must be arranged in such a manner close to the centrifuge that the cooling liquid cannot discharge therethrough. Closest to the centrifuge, therefore, the pipes should extend upward from the machine.

There is the same risk of a deterioration of the tightening material in case the supply of liquid being treated in the centrifuge should be interrupted, for any reason, after the centrifuge has been started. It is often necessary, particularly in dairies, to so interrupt the operation of the machine. The present invention also comprises a method and means for cooling the packing boxes during such interruption. The specific embodiments of the invention hereinafter described insure a sufficient circulation of liquid through the centrifuge upon cessation or interruption of the supply of such liquid treated in the centrifuge as well as during the starting operation.

The full object of the invention may be attained in many different ways. For instance, a return pipe may be arranged from one or more of the outlets of the centrifuge to its inlet. As centrifuges of this type usually are provided with

a pump which forces the liquid through the centrifuge under a comparatively high pressure, the return pipe should of course be connected to the inlet side of the pump. A valve may also be arranged in the return pipe which should normally be closed but may be opened when required. Such a simple device would, however, scarcely suffice to insure an uninterrupted circulation of liquid through the centrifuge, since the operator cannot always be depended on to observe when the supply of liquid to the centrifuge ceases and to then open the valve. The arrangement therefore involves some risk of the packings being damaged. A continuous flow of liquid through the centrifuge may of course be insured by allowing the return pipe to be always open, but a corresponding capacity of the centrifuge is then lost. While the present invention, in its broader aspect, contemplates the employment of a return pipe that is maintained open, its preferred embodiments include means whereby a cooling liquid is automatically fed into the centrifuge and made to circulate therethrough when, for any reason, the normal supply of liquid under treatment is interrupted or substantially reduced. On such occasions the pressure in the supply pipe of the centrifuge drops towards nil. In the preferred embodiments of the invention, there is provided a regulating apparatus which reacts to the pressure and in turn controls a valve or valves for the cooling liquid, which may consist of separated liquid or a special cooling liquid, for instance, water from a water pipe. In the former case the regulating apparatus, at the proper time, automatically opens valves in the pipes which run from the outlet pipes of the centrifuge to the inlet of the centrifuge. In the latter case, the regulating apparatus opens a valve, for instance to the water pipe, so that water circulates through the centrifuge. In this case the regulating apparatus may also be arranged to shut the outlet pipes of the centrifuge and open special outlets for the cooling water.

In another embodiment of the invention there is provided, in the neighborhood of the centrifuge, a container from which liquid is, at the proper time, automatically fed into the centrifuge by the regulating apparatus. The container may stand by itself, or it may be combined with one of the outlet pipes of the centrifuge in such a manner that already centrifugated liquid is utilized for the cooling. In the latter case, and particularly when no container is provided, it is desirable to interpose in the conduit for cooling liquid a cooler which lowers the temperature of the liquid before it again enters the centrifuge. Without re-cooling, the cooling liquid would slowly be heated by the frictional heat generated in the packing boxes to such a high temperature that its cooling quality would be lost.

The accompanying drawings show a number of different embodiments of the invention.

Figs. 1, 2 and 3 are diagrams illustrating different embodiments of the invention.

Fig. 4 is a vertical sectional view of a modification wherein the valves and the regulating apparatus therefor are built in a unitary structure.

Figs. 5 and 6 are respectively horizontal and vertical sections through another similar structure.

Figs. 7 and 8 are respectively horizontal and vertical sections through still another similar unitary structure.

Fig. 9 is a vertical sectional view through a

typical packing box for a centrifuge of the "closed" type.

In the embodiment shown in Fig. 1, a pump 1 forces the liquid through a pipe 2 into the centrifuge 3, from which two separated components 5 discharge, for instance cream and skim milk, through pipe lines 4 and 5 respectively, the latter, for instance, being intended for the milk. To the pipe line 5 is connected a pipe 6 through which part of the skim milk may be led back to 10 the inlet side of the pump.

In the embodiment shown in Fig. 2 one or more return pipes are automatically opened when the feed of liquid to be treated falls below normal. The supply pipe 2 of the centrifuge communicates by a pipe line 7 with a regulating apparatus 8 which effects the control of the valves for the cooling liquid. The regulating apparatus consists, for example, of a cylinder provided with a piston 9 acting on valves 10 and 11 in pipe lines 20 12 and 13 respectively. The pipe lines 12 and 13 are connected to pipe lines 4 and 5 respectively. The pipe lines 12 and 13 open over a funnel 14 connected with the pipe line 60. As long as the pressure in the pipe lines 2 and 7 respectively 25 is normal, the piston 9 is maintained in its upper position and the valves 10 and 11 are closed. When the pressure in the pipe line 2 drops, the piston 9 moves downward under the influence of a counter-weight 15 positioned on the lever of 30 the valve 11. The valves in pipe lines 12 and 13 are then opened so that separated liquid can be supplied to the pump and the centrifuge through the funnel 14 and the pipe line 60. In this way a continuous circulation of liquid 35 through the packing boxes of the machine is insured. As the cream and the skim milk stream down into the funnel in free jets, it is impossible for the cream to enter the skim milk outlet, or the reverse. With this arrangement there is obtained the additional advantage that the jets indicate any interruption in the milk supply, as they are well visible. Any other device acting in the same manner may of course be substituted for the regulating devices 8 and 9. Instead of a 40 piston, a membrane or slide, of the character of those hereinafter described, may be used.

In the embodiment shown in Fig. 3, the cooling liquid is taken from a skim milk container 16, which may be positioned on a higher level 50 than the centrifuge. The container is connected to the discharge pipe 5 for skim milk from the centrifuge and to a pipe line 17, connected with the pump 1. In pipe line 17 is interposed a cooler 18 and a valve 11. The cream discharge pipe 4 55 is provided with a valve 19. Through suitable mechanical connections 61 the regulating apparatus 9 closes valve 19 at the same time that it opens valve 11. The container 16 is provided with a level outlet over which the skim milk dis- 60 charges to the pipe 20. The level in the container 16 is thus constant as long as liquid is not removed therefrom and circulated through the centrifuge, thereby insuring the maintenance of a sufficient quantity of skim milk in the container if an interruption should occur in the supply of whole milk. A similar liquid accumulating container may be connected with the cream outlet in substitution for, or in addition to, the container 16. It is not necessary to close the 65 pipe 4 at the same time as the return pipe for skim milk is opened. However, if the cream pipe is not then closed, part of the skim milk will discharge through the cream outlet from the centrifuge; and if the machine should run empty 70 75

for some length of time the container 16 may become quite empty if the cream outlet 4 be open. The automatically shut valve 19, although generally not necessary, is decidedly advantageous.

It is possible, and also advantageous, to associate, in a unitary structure, the regulating apparatus 8 and the valves 10, 11 and 19. Of these valves the valve 10, which controls the return flow of the cream, may often, for instance in purifiers, be dispensed with, so that only a part corresponding to the valve 11 need be retained. Such an arrangement is shown in Fig. 4. The apparatus comprises a membrane 21, suitably of heavy rubber, and fixed between two sections of a housing 22 and 23. The upper side of the membrane is subject to pressure from the supply pipe 2, which communicates with the membrane through a pipe line and the channel 24 in the housing. Beneath the member is a spring 25, which is in contact with the membrane through a part 26 and tends to lift it against the pressure from the pipe 2. In the figure, the membrane is in the position that it occupies during normal operative conditions, in which position the superior pressure in the pipe 2 shuts the orifice of a nozzle 27 in the housing, the lower end of which nozzle is connected with the outlet pipe of the centrifuge. The throughflow area of the nozzle may be varied by means of a screw 28. When the pressure in the channel 24 disappears or is reduced to a predetermined degree, the membrane 21 is forced upward by the spring 25 so that the nozzle 27 is brought into communication with a channel 29, which is connected with the inlet side of the pump 1. Thereby a circulation of liquid is established through the packing of the centrifuge.

In a milk centrifuge having closed outlets for skim milk and cream, it is of course necessary to insure a sufficient cooling also of the cream outlet. It may then be necessary, and in any case safest, to provide for a liquid circulation also in the cream passage. This may be effected by opening a return pipe from the cream outlet pipe as set forth in the description of Fig. 2. Figs. 5 and 6 show automatically operating valve mechanism for establishing such return passages both for cream and skim milk. The valve consists of a cone-shaped rubber capsule 30, which also serves as a membrane and which is pressed against grooves 31, 32 and 33 in a cone-shaped valve housing 34 by the pressure from the pipe 2 transmitted through a channel 35. The groove 31 opens into a channel 36, which is designed to be connected with the inlet of pump 1. The grooves 32 and 33 communicate with the skim milk and cream outlets respectively. The capsule may suitably be filled up or strengthened by a solid body 37 having the same shape as the valve housing. A spring 38 is adapted to move the capsule from the grooves 31 to 33 when the pressure in the channel 35 disappears or is reduced to a predetermined degree.

Figures 7 and 8 show a modification of the construction of Figs. 5 and 6. A channel 39 is adapted for connection with the inlet side of pump 1. A slide or piston 40 is subjected on its upper side to the pressure from the supply pipe 2 of the centrifuge and on its lower side to the pressure of a spring 41. When the pressure in the supply pipe drops, slide 40 is pressed upward against a shoulder 42 by the spring 41 and communication is established, by means of an annular

groove 43 in the slide, between grooves 32 and 33 and channel 39.

While the described embodiments of the invention are adapted to automatically maintain a circulation of cooling fluid through the packing boxes of the centrifuge whenever the supply of liquid to be separated or purified is below a predetermined minimum, either when the centrifuge is speeding up preparatory to admitting the liquid to be treated, or when there is an interruption in, or cessation of, the supply of liquid to be treated, it is possible, although much less desirable, to control the admission and circulation of liquid, during either or both, of these periods, entirely manually. This may be done in different ways. For example, in Fig. 1 I have shown manually operable valves 70, 71 and 72 on pipes 5, 4 and 6 respectively. During speed up of the centrifuge, valves 70 and 71 may be closed and valve 72 opened. After the centrifuge has attained the speed at which it is desirable to admit liquid to be treated, valve 72 is closed and valves 70 and 71 are opened. If it is desired that the cooling liquid shall be some other liquid than that to be treated, such cooling liquid may be supplied through a pipe 74 controlled by a valve 73. In either operation an endless circulation of cooling liquid will be maintained through pipe 2, the packing boxes of the centrifuge and pipe 6 back to pump 1. A cooler, like that shown at 18 in Fig. 3, should be interposed in pipe 6.

Centrifuges wherein the discharging liquids flow through packing boxes are well understood in the art and need not be described in detail. In Fig. 9 such packing boxes, adapted to "closed" centrifuge, are shown. Through the neck of the separator bowl 80 is discharged the lighter separated constituent into the pipe 4 communicating with a space containing packing 84. Through channels 81 communicating with the peripheral portion of the bowl is discharged the heavier separated constituent into a chamber 82 containing packing 85 and communicating with the pipe 5. The specific packing box shown in this figure forms the subject matter of an application filed by me September 18, 1931, Serial No. 563,540, now matured into Patent No. 2,002,954, dated May 28, 1935.

What I claim and desire to protect by Letters Patent is:

1. The combination with a centrifuge provided with an inlet and an outlet and comprising packing means with which outflowing liquid contacts, of a supply pipe for liquid to be separated an auxiliary pipe adapted to convey a cooling liquid, both said pipes communicating with the packing means of the centrifuge, and means controlled by the pressure in the supply pipe to maintain said auxiliary pipe closed during normal flow toward the centrifuge of liquid to be treated and to open said auxiliary pipe to admit cooling fluid to the centrifuge when the input of liquid to be treated falls below a desired minimum, thereby insuring cooling of the tightening surfaces between rotary and stationary parts in the packing means while the separator is operating during the period of reduced or no inflow of liquid to be treated.

2. The combination with a centrifuge provided with an inlet and an outlet and comprising packing means with which outflowing liquid contacts, of a pipe adapted to convey a cooling liquid and communicating with the packing means of the centrifuge, and means to maintain said pipe closed during normal flow toward the centrifuge.

of liquid to be treated and to open said pipe to admit cooling fluid to the centrifuge when the input of liquid to be treated falls below a desired minimum, thereby insuring cooling of the tightening surfaces between rotary and stationary parts in the packing means while the separator is operating during the period of reduced or no inflow of liquid to be treated, said means comprising a regulating apparatus connected with both the centrifuge inlet and said cooling liquid pipe and adapted to be controlled by the pressure of liquid flowing toward the centrifuge.

3. The combination with a centrifuge, an inlet pipe for conveyance to the centrifuge of liquid to be treated, an outlet from the centrifuge and packing means with which outflowing liquid contacts, of a return flow pipe connecting said outlet with said inlet, a valve in said return flow pipe, and a regulating apparatus connected with both the valve in the return flow pipe and the centrifuge inlet pipe and operable by the pressure in said inlet pipe to control the opening and closing of said valve.

4. The combination with a centrifugal separator, of an inlet pipe for conveyance to the separator of liquid to be separated, outlets from the centrifuge for respectively heavier and lighter separated liquids, and packing means with which outflowing liquid contacts, of a return flow pipe connecting one of said liquid outlets with the separator inlet, a valve in said return flow pipe and a valve controlling the outlet for the other liquid and means controlled by the opening of the first named valve to close the second named valve.

5. The combination with a centrifugal separator, of an inlet pipe for conveyance to the separator of liquid to be separated, outlets from the centrifuge for respectively heavier and lighter separated liquids, and packing means with which outflowing liquid contacts, of a return flow pipe connecting one of said liquid outlets with the separator inlet, a valve in said return flow pipe, and a regulating apparatus connected both with said valve and said inlet pipe and adapted to control the operation of said valve by the pressure of liquid in said inlet pipe.

6. The combination with a centrifugal separator, of an inlet pipe for conveyance to the separator of liquid to be separated, outlets from the centrifuge for respectively heavier and lighter separated liquids, and packing means with which outflowing liquid contacts, of a return flow pipe connecting one of said liquid outlets with the separator inlet, a valve in said return flow pipe, and a valve controlling the outlet for the other liquid, and a regulating apparatus connected with both said valves and with said inlet pipe and adapted to control the operation of said valves by the pressure of liquid in such inlet pipe.

60 7. The combination with a centrifugal separator, an inlet pipe for conveyance to the separator of liquid to be separated, outlets from the centrifuge for separated liquids, and packing means with which outflowing liquid contacts, of means operable by the pressure in the inlet pipe to divert the liquids discharged through said outlets to the centrifuge inlet, said liquid diversion means comprising return flow pipes connected with the respective outlets and a funnel into which said diverted liquids discharge, so that return flow liquids may stream in free and visible jets into the funnel and preventing the streaming of liquid from one outlet to the other.

75 8. The combination with a centrifuge provided

with an inlet and an outlet and comprising packing means with which outflowing liquid contacts, of a pipe adapted to convey a cooling liquid and communicating with the packing means of the centrifuge, and means to maintain said pipe closed during normal flow toward the centrifuge of liquid to be treated and to open said pipe to admit cooling fluid to the centrifuge when the input of liquid to be treated falls below a desired minimum, said means comprising a housing having openings communicating respectively with said inlet, said cooling liquid pipe and said outlet, and means in said housing closing communication between the first two openings and normally closing communication between the last two openings and operable, by a predetermined drop in pressure in said inlet, to open communication between the last two openings.

9. The combination with a centrifuge provided with an inlet and an outlet and comprising packing means with which outflowing liquid contacts, of a pipe adapted to convey a cooling liquid and communicating with the packing means of the centrifuge, and means to maintain said pipe closed during normal flow toward the centrifuge of liquid to be treated and to open said pipe to admit cooling fluid to the centrifuge when the input of liquid to be treated falls below a desired minimum, said means comprising a housing having openings communicating respectively with said inlet, said cooling liquid pipe and said outlet, means in said housing closing communication between the first two openings, and a spring tending to operate said means to open communication between the last two openings, said spring being prevented from so operating by the inlet pressure operating through the first opening unless said pressure drops below a predetermined minimum.

10. In combination with a centrifugal separator having packing means requiring cooling by liquid flowing through said separator and a primary pipe system normally open for flow to the separator inlet of liquid to be separated, a secondary pipe system adapted to convey a cooling liquid in contact with said packing means and normally closed against any flow and means, operable by reduction of pressure in said primary system, to open said secondary system for flow until restoration of pressure in said primary system.

11. The combination with a centrifugal separator provided with an inlet and an outlet and comprising packing means with which outflowing separated liquids contact, of a supply pipe adapted to convey liquids to be separated to said inlet, means adapted to divert a portion of one of the separated liquids to the inlet side of the centrifuge and to throttle the discharge of the other separated liquid, and means, controlled by the pressure of the liquid to be treated flowing toward said inlet, to simultaneously actuate said diverting and throttling means.

12. In the operation of centrifuges comprising a packing box with which discharging liquid contacts, the herein described process of preventing damage to the packing box while the centrifuge is operating during the period when the liquid to be treated is not being supplied thereto or is being supplied thereto at a subnormal rate below a predetermined minimum rate, said process comprising flowing a cooling liquid through said packing box during said period, flowing the liquid to be treated toward the centrifuge, shutting off said flow of cooling liquid while the liquid to be

treated is being supplied at not below said predetermined minimum rate, and controlling said flow of cooling liquid, during said period of subnormal flow of the liquid to be treated, by the 5 reduced pressure of the liquid to be treated flowing toward the centrifuge inlet.

13. In a centrifuge provided with an outlet for treated liquid and comprising packing means with which outflowing liquid contacts and a 10 source of supply for liquid to be treated connected with the centrifuge, the herein described means of preventing damage to said packing means while the centrifuge is operating during the period when the liquid to be treated is not 15 being supplied thereto or is being supplied thereto at a subnormal rate below the predetermined rate, said means comprising a source of supply of cooling liquid and a connection therefrom to the centrifuge, a device operable to shut off the flow 20 of cooling liquid to the centrifuge while the liquid to be treated is being supplied at not below said predetermined minimum rate, and means, controlled by the reduced pressure of the liquid to be treated flowing toward the centrifuge during its 25 said period of subnormal flow, to operate said device to allow flow of cooling liquid to the centrifuge.

14. The combination with a centrifuge having packing members liable to damage by excess 30 heat, a closed feed passage and a closed discharge passage, of a cross passage through which discharged liquid is adapted to flow from the discharge passage to the feed passage, and means, controlled by pressure of the liquid to be treated 35 flowing toward the centrifuge, to shut off said flow through said cross passage while the liquid to be treated is being supplied at not below a predetermined minimum rate and to open said cross passage to said flow when the supply of 40 liquid to be treated falls below said predetermined rate.

15. The combination with a centrifuge having packing members liable to damage by excess heat, a closed feed passage and a closed discharge passage, of a cross passage through which discharged liquid is adapted to flow from the discharge passage to the feed passage, a valve controlling the flow of liquid through said cross passage, and means, controlled by excess of pressure in the feed passage over that in the discharge passage, to hold said valve closed while 10 the liquid to be treated is being supplied at a normal rate and to open said valve upon reduction of pressure due to reduction of feed of liquid to be treated to allow an endless circulation of liquid through said passage and centrifuge to 15 maintain said packing members cool.

16. The process of preventing overheating of the packing members of a closed centrifuge which comprises flowing liquid to be treated into said centrifuge and discharging centrifugally treated 20 liquid therefrom and in the course of its said flow contacting liquid with said packing members, returning discharged liquid to the centrifuge when the flow of the liquid to be treated is arrested or reduced below a predetermined rate and utilizing 25 the pressure of inflowing liquid to be treated to arrest said return of discharged liquid during inflow of the liquid to be treated at not below said predetermined rate.

17. The process of preventing damage to the 30 packing members of a closed centrifuge which comprises flowing the liquid being centrifugally treated in contact with such members, discharging treated liquid independently of the inflow of liquid to be treated while said inflow is proceeding 35 at a normal rate, returning discharged liquid to the centrifuge inlet when said inflow of liquid to be treated is reduced below the normal rate, and utilizing the pressure of inflowing liquid to be treated to govern said discharge. 40

HANS OLOF LINDGREN.
